ARTIFICIAL LIMB

Charles H. Bennington, Wantagh, and James N. Tilley, Valley Stream, N. Y., assignors to The Modern Limb Supply Co., Inc., Wantagh, N. Y., a corporation of New York

Application April 5, 1951, Serial No. 219,386

7 Claims. (Cl. 3—33)

1

This invention has to do with an artificial limb and in particular with an artificial limb having an ankle and foot capable of simulating many of the movements of a natural limb.

In normal walking the foot has at least six different movements: dorsal and plantar flexion, pronation and supination in the hind foot, and flexion in both directions of the metatarsals and toes in the forefoot. The problem of providing an artificial limb capable of all these movements is an old one, and ball and socket joints, bearings, springs, connections of various resilient materials and many other suggestions have been made for simulating the natural movements. The commonest objections to prior artificial limbs have been their inability to perform in a manner comparable to a natural foot, and to stand up under the heavy wear and strain to which they are subjected.

An object of the present invention is to provide in an artificial limb a rugged, simple connection between the parts representing the shin bone or tibia and the foot, permitting the foot to be moved in a manner closely resembling that of a natural foot. This object is attained by providing a block of resilient material having rigid plates embedded therein and flexibly connecting the tibia to the foot.

According to other features of the invention the metatarsal section is made flexible, and a heel cord is provided which can be readily adjusted to vary its tension.

These and other features of the invention will be more fully described in connection with the drawings, in which:

Fig. 1 is a side elevation showing a limb according to the invention;

Fig. 2 is a side elevation of the limb partly in section; and

Fig. 3 is perspective of the pantalar articulation according to the invention.

Referring to Fig. 2, a foot member 10 is made from any suitable hard, relatively light material, such as wood. The anterior portion of the foot has two slots 11 and 11a. Slot 11 is at a point in the foot corresponding to the break at the base of the metatarsal and slot 11a corresponds to the break at the toe joint. Slot 11a is approximately 25% wider at its opening or top 0 than slot 11, thereby permitting the foot in walking to roll forward to approximate the natural flexion at the respective joints. In an artificial foot for the average male adult, slot 11 will be $\frac{7}{8}$ " across the opening and slot 11a $\frac{1}{2}$ " wide. A cavity 13 in midtarsal section 14 and a cavity 16 in toe sec-

2

tion 17 register with a hollow portion 15 in metatarsal 12. An elongated resilient member 18, of rubber or the like, is loosely inserted in cavities 13 and 16 and hollow portion 15. The portion of member 18 lying in metatarsal 12 has a concavity 18a to insure firm anchoring of rubber 18 in cavities 13, 15 and 16 during walking. A pliable sole 19 recessed in the midtarsal section 14 and toe section 17, is secured with the resilient member 18 to the midtarsal, metatarsal and toe sections 14, 12 and 17 respectively by means of screws 20 or the like.

The pantalar articulation comprises a block 21 of resilient material, preferably natural or synthetic rubber, such as that used in first line automobile tires. While block 21 will here and in the claims be referred to as being made of rubber, it is understood that any other material having resilient characteristics such as rubber could be used. By pantalar is meant the joints and tissues surrounding the talus. The term pantalar articulation is used to describe an element which can be moved to simulate most of the movements of the talus and oscalcis. The resiliency of rubber block 21 should be about the same throughout, but the resiliency of each block should preferably vary depending on the age, weight and activity of the wearer of the limb. For instance, in the case of a normally active adult of 200 pounds for whom the limb being described will be considered, the block should have a durometer reading of 50.

Referring to Fig. 3, the upper surface of block 21 is V-shaped and consists of front portion 22 and rear portion 23 which slope towards the opposed lower horizontal surface. Preferably front portion 22 is slightly, about 12%, longer than rear portion 23. By way of example some of the dimensions of block 21 are as follows:

	Inches
(a) Length of portion 22	$1\frac{3}{8}$
(b) Length of portion 23	$1\frac{1}{4}$
(c) Length of lower surface	$2\frac{7}{8}$
(d) Narrowest distance between upper and lower surfaces	$\frac{1}{16}$
(e) Maximum distance between portion 22 and lower surface	$1\frac{5}{8}$
(f) Maximum distance between portion 23 and lower surface	$1\frac{5}{8}$
(g) Width at juncture of portions 22 and 23	$1\frac{1}{8}$

The angle which portions 22 and 23 (the legs of the V) make with one another is determined by the thickness of rubber required between the

upper and lower surfaces of block 21. This will vary as previously pointed out with the weight, age and activity of the wearer of the limb. However, in all cases it is desirable to keep this thickness to a minimum in order to insure that the pivoting point of the leg will be as close to the foot as possible as in the natural pantalar joints.

A thin plate 24, of the order of $\frac{1}{16}$ " thick, of metal or other rigid material, e. g. bronze, is bonded into block 21 just below and parallel to the surfaces of portions 22 and 23. Plate 24 is preferably one piece which has been bent to conform the V-shaped upper surface of the block.

Another plate 25, similar to plate 24, is bonded into block 21 just above and parallel to its flat lower surface. Two bolts 26 are brazed to plate 25 and project therefrom. Two bolts 27 are brazed to the front of plate 24 and project therefrom as do two other bolts 28 brazed to the rear of plate 24.

Bolts 26, 27 and 28, respectively, serve as the means for fastening block 21 to the foot and leg, and plates 24 and 25 the means for anchoring the bolts in the block. While other fastening and anchoring means are possible according to the invention, it is important that the connection between the leg and foot be secure yet not rigid.

The bonding of plates 24 and 25, with their respective bolts extending therefrom, into block 21 may be done in any one of a number of well known ways.

In the embodiment of the invention here illustrated, plate 24 is about $\frac{1}{16}$ " in thickness and plate 25, $\frac{3}{32}$ " thick. Plate 25 is preferably made of slightly heavier stock than plate 24 because it is fastened to the foot by only two bolts 26, whereas plate 24 is fastened to the leg by four bolts 27, 28. While both plates are substantially co-extensive with their parallel block surfaces and are embedded in the block about $\frac{1}{8}$ " from the nearest outside surface, they could be at a greater or a lesser distance therefrom. The plates could also be merely bonded or otherwise fastened to the upper and lower surfaces of the block. The important point is to guard against the plates being torn away from the block as a result of the heavy strain to which they are subjected during use of the artificial leg. Embedding them is one good way of preventing this.

The leg, tibia or shin bone is divided into a hollow upper portion 31 and a lower portion 32 which telescopes into portion 31. By means of bolts 33 and flange 34 on upper portion 31 the position of lower portion 32 may be adjusted therein to vary the length of the leg depending on the requirements of the wearer. Base 35 of portion 32 is V-shaped to correspond to upper surfaces 22 and 23 of block 21. It will be noted that edge 36 of front portion 22 extends beyond base 35 because front portion 22 is slightly, about 12%, longer than rear portion 23. The reason for making front portion 22 longer than rear portion 23 is that in plantar flexion the front of block 21 undergoes greater strain and must stretch more than in dorsal flexion, because in the latter the heel cord acts as a restraint.

Suitable holes to accommodate bolts 26 extend through foot 10 and terminate in cut-out 37 in the bottom of foot 10. Nuts 38 may be screwed onto the ends of bolts 26 and work against a plate 39 to hold the block securely on the foot. Similarly, holes extending through base 35 permit bolts 27 and 28 to extend therethrough and the block is securely held to the lower portion of the tibia by nuts 40.

It will be appreciated that an important feature of block 21 is that it provides in a single, relatively inexpensive unit a pantalar articulation where heretofore a plurality of complicated parts was necessary. Furthermore, block 21 may be easily replaced with another block by the wearer if it becomes worn or breaks.

A heel cord 42 is connected between a hook 43 formed on bracket 44 secured to the posterior of tibia portion 32 and an adjustable screw mechanism in the heel of the foot. The adjustable screw mechanism operates in a hole 45 extending through the bottom of heel 46 and contains an internally threaded flanged bushing 47 having holes 48 in its flanged end whereby bushing 47 may be turned by means of a spanner wrench or key (not shown). Ends 49 of cord 42 are secured in an externally threaded ferrule 50 and held therein by an anchored pin 51 which rests against shoulder 52 in pipe 53. Threaded members 47 and 50 cooperate so that when member 47 is turned the tension on heel cord 42 will be varied. It is important that the wearer of the artificial limb can easily adjust the tension of the heel cord himself without recourse to others.

While I have shown cord 42 as made from fibrous material with a leather covering 53, it may be made from any other suitable inelastic material.

It will be appreciated that the metatarsal section, pantalar articulation and heel cord here described combine to provide an artificial limb whose foot portions mechanically simulate many of the movements of a natural foot. While any one of the three above described improvements may be incorporated individually in an artificial limb, the combination of all three of these constitutes an important feature of the invention.

Terms such as tibia, foot, heel, etc. used in the claims designate mechanical simulations which perform some of the functions of the natural members.

What is claimed is:

1. In an artificial foot, two slots of different widths in the front portion of said foot defining a metatarsal section, a hole through said metatarsal section and cavities registering therewith in the toe and midtarsal sections of the foot on either side of the metatarsal, and a piece of flexible material extending through said hole and cavities.

2. An artificial foot comprising a toe, a metatarsal and a midtarsal section, a first slot between said toe and metatarsal sections, a second slot narrower than said first slot between said metatarsal and midtarsal sections, a hole in said metatarsal registering with cavities in the toe and midtarsal sections, and a piece of flexible material extending through said hole and cavities whereby in walking the front portion of the foot simulates some of the movements of a natural foot.

3. In an artificial limb, a pantalar articulation connected between the tibia and the foot comprising a block of rubber having a V-shaped upper surface and a relatively flat lower surface, the upper surface contacting the tibia member and divided into a front and a rear portion sloping towards the lower surface, the front portion being of the order of 12% longer than the rear portion, the lower surface of said block contacting the foot member, a first metal plate embedded in said block just below and parallel with the upper surface, a second metal plate embedded in the block just above and parallel with the lower surface, fastening means projecting from both

said plates for fastening said block to the tibia and foot members, a heel cord connected between said tibia and the heel portion of said foot, and an adjustable screw in a hole in the bottom of the heel connecting said cord to the heel whereby the tension exerted by said cord may be varied.

4. In an artificial limb, a leg member having an upper portion and a lower portion telescoping therein to adjust the length of said leg, a foot member, a pantalar articulation between said last two mentioned members comprising a block of automobile tire grade rubber having an upper surface contacting the lower leg member and divided into front and rear portions angularly disposed with respect to each other to resemble a V, said front portion being of the order of 12% longer than said rear portion and extending said amount free from said lower leg member when the upper surface of the block is in contact therewith, the lower surface of said block being substantially flat and contacting the foot member, a first bronze plate embedded in said block just below and parallel with the upper surface, a second bronze plate embedded in the block just above and parallel with the lower surface, bolts extending from both of said plates for fastening said block to the leg and foot, a heel cord of relatively inelastic material connected between the lower rear portion of said leg and the heel of the foot, an adjustable screw mechanism in a hole in the bottom of the heel for connecting the cord to the heel whereby tension exerted by said cord may be varied, the front portion of said foot being divided by two slots into a metatarsal, a midtarsal and a toe section, the anterior of said slots being of the order of 25% wider at its top than said posterior slot, a hollow portion extending through said metatarsal section and cavities corresponding therewith in said midtarsal and toe sections, a piece of rubber extending through said cavities and hollow portion and having a concavity in the portion in the metatarsal, and a sole of pliable material covering the bottom of said foot portions through which said piece of rubber extends.

5. An artificial foot comprising complementary toe, metatarsal and midtarsal sections having angular end faces disposed in spaced, end to end

relation, each of said sections being recessed inwardly of its bottom face, a block of resilient material common to said sections disposed in said recesses in section spanning relation, a yieldable sole member recessed in said toe and midtarsal sections in overlying relation to said resilient material, and a plurality of screws securing said sole member and said block of resilient material to said toe, metatarsal and midtarsal sections.

5 10 6. The invention according to claim 5, and in which the surface juncture between said metatarsal section and said block of resilient material is at least in part concavo-convex.

7. In an artificial limb, the combination of a 15 longitudinally adjustable leg member terminating in a V-shaped end portion, a foot member including a toe section and a metatarsal section yieldably connected thereto in spaced end to end relation, a pantalar connection between said V-shaped end portion and said foot member comprising a block of resilient material having a horizontal bottom face and a complementary V-shaped upper face, a plurality of oppositely extending stud screws bonded in said block securing it to said V-shaped end portion and to said foot member, a rearwardly extending hook member secured to said adjustable leg member, a shouldered, internally threaded bushing revolvably seated in the heel portion of said foot member flush therewith, and a looped cord having its free ends secured in an externally threaded ferrule adjustably connected to and between said hook member and said bushing.
